[57]**CLAIM**

We claim the ornamental design for a pet toy with the face of a rabbit, as shown and described.

DESCRIPTION

FIG. 1 is a front view of a pet toy with the face of a rabbit showing our new design;

FIG. 2 is a left side elevational view thereof, the right side being a mirror image;

FIG. 3 is a rear elevational view thereof;

FIG. 4 is a top plan view thereof; and,

FIG. 5 is a bottom plan view thereof.
